UNITED STATES PATENT OFFICE

ALEX H. OLSON, OF EVANSTON, ILLINOIS, ASSIGNOR TO JOSEPH W. DROLL, OF CHICAGO, ILLINOIS

PROPELLER WHEEL FOR FANS

Application filed November 6, 1931. Serial No. 573,318.

The invention relates to propeller wheels for fans.

It is now common practice to provide stationary deflectors in front of the propeller wheels of ventilating fans to deflect the air projected axially by the fan obliquely outward to spread the air over a wide area.

The primary object of the invention is to provide a propeller wheel which is provided with blades which will efficiently spread the air over a widely flared zone to distribute it over a large portion of the room, so that separate deflectors for this purpose can be dispensed with. Another object is to provide a propeller wheel for fans which will operate efficiently. Other objects will appear from the description.

The invention consists in the several novel features hereinafter set forth and more particularly defined by claims at the conclusion hereof.

In the drawing: Fig. 1 is a front elevation of a fan embodying the invention. Fig. 2 is a side elevation. Fig. 3 is a front view of one of the propeller blades. Fig. 4 is a rear end view of one of the blades. Fig. 5 is a plan of one of the blades. Fig. 6 is a section on the line 6—6 of Fig. 3. Fig. 7 is a section on the line 7—7 of Fig. 3.

The invention is exemplified in a propeller wheel secured to the shaft 10 of an electric motor 11 which may be of any suitable construction. The wheel comprises a series of four blades 14 which are preferably formed

of sheet metal. The inner ends of the blades are secured to radial lugs on a hub 12 which is fixed to the shaft 10. These blades are identical in construction so that a description of one applies to all. Each blade com-

prises an inner member or portion 15, a tip member or portion 16 and an intermediate member or portion 17. The inner member 15 increases in width from its inner end, and its face is inclined transversely to the plane of rotation, as shown in Fig. 7, to propel the air forwardly of the wheel while the latter is rotated. The front face of member 15 is also inclined frontwardly as shown in Fig. 6,

to propel the air slightly toward the center of the fan and prevent a dead-air space in

front of the center of the fan. The front edge 15^a and the rear edge 15^b of member 15 are helical or curved or sloped rearwardly with respect to a diametric line. The front face of the intermediate member 17, which may for descriptive purposes be regarded as connecting with the member 15 on the line 18—18 of Fig. 3, is tangential or inclined to the plane of rotation of the wheel, and its outer portion is curved rearwardly axially to provide a surface which will propel the air obliquely frontwardly and outwardly in gradually increasing degree from the axis of the wheel. The front edge 17^c and the back edge 17^d of the intermediate member 17 are also helical or curved backwardly relatively to a diametric line and in the plane of rotation to cause the blade to act on the air progressively in the rotation of the wheel. The air tends to slide radially outward and backwardly over the front face of the inner portion of the member 17, and this formation causes the air to be effectively propelled obliquely forward. The tip member 16, which may for descriptive purposes be regarded as merging with the intermediate portion on the line 19—19 of Fig. 5, is extended to trail the member 17 in the rotation of the wheel, is curved longitudinally of the axis and the same as the outer end of the member 17. The tip is tangential to render it effective in propelling the air outwardly from the axis of the wheel. Its edges 16^a and 16^b terminate in a point 16^c. The tip constitutes a sweep-back formation to act successively on the air which has a tendency to slide over the front face of the blade.

In operation the inner members 15, by reason of their transverse inclination and their frontward and outward inclination propel air frontwardly and sufficiently towards the axis to prevent the formation of a dead-air space in the central zone in front of the wheel. The intermediate members 17, by reason of being tangential and their axially rearward slope, propel the air obliquely frontwardly and outwardly from the axis progressively increasing degrees to distribute the air through a wide conoidal zone. By reason of the sweep-back of the medial portion, the air

slipping along their faces will be effectively propelled by these members. The tips which trial and intermediate portions in the rotation of the blades render them more effective in 5 propelling the air in the outer portion of the conoidal zone of air propelled by the wheel and prevent the formation of eddy currents which would lessen the efficiency of the intermediate members of the blades. The wheel 10 in its entirety propels a substantially conoidal 90° zone of air as indicated in Fig. 2, with substantially uniform pressure throughout the entire zone and thus effects the desired wide distribution of the air under moderate 15 pressure over a wide area in a room.

The invention exemplifies an air propeller or fan-wheel in which the blades are formed to distribute the air over a wide area and makes it possible to accomplish this result 20 without the use of supplemental stationary devices, such as deflectors, and also renders it unnecessary to provide mechanism for moving the fan in order to attain the desired distribution of the air throughout the room.

25 The invention is not to be understood as restricted to the details set forth, since these may be modified within the scope of the appended claims, without departing from the spirit and scope of the invention.

30 Having thus described the invention, what I claim as new and desire to secure by Letters Patent, is:

1. As a new article of manufacture, a wheel 35 for propelling air comprising a hub adapted for connection to a drive shaft, and a plurality of blades connected to and projecting outwardly from the hub, each of said blades consisting of an outwardly flared, transversely inclined inner part extending outwardly from 40 the hub and having the leading and trailing edges thereof curved rearwardly with respect to the direction of rotation of the wheel in a substantially spiral manner, an intermediate part extending outwardly and backwardly 45 from the outer portion of the inner part and

rearwardly with respect to the direction of rotation of the wheel and shaped so as to propel another portion of the propelled air forwardly and outwardly in gradually increasing degree from the axis of rotation, and a 70 tapered tip extending backwardly from the rearmost portion of the intermediate part substantially longitudinally with respect to the axis of rotation of the wheel constituting a sweep-back formation whereby the air sliding off the rearmost part of the intermediate part is deflected outwardly during rotation of the wheel. 75

2. As a new article of manufacture, a wheel for propelling air comprising a hub adapted for connection to a drive shaft, and a plurality of blades connected to and projecting outwardly from the hub, each of said blades consisting of an outwardly flared, transversely inclined inner part extending outwardly and slightly forwardly from the hub so as to deflect a portion of the propelled air inwardly towards the axis of rotation and prevent the formation of a dead-air space in front of the center of the wheel and having the leading and trailing edges thereof curved rearwardly with respect to the direction of rotation of the wheel in a substantially spiral manner, an intermediate part extending outwardly and 85 backwardly from the outer portion of the inner part and rearwardly with respect to the direction of rotation of the wheel and shaped so as to 90 propel another portion of the propelled air forwardly and outwardly in gradually increasing degree from the axis of rotation, and a tapered tip extending backwardly from the rearmost portion of the intermediate part substantially longitudinally with respect to the axis of rotation of the wheel constituting a sweep-back formation whereby the air sliding off the rearmost part of the intermediate part is deflected outwardly during rotation of the wheel. 95
